Primary Examiner — Raphael Barkai*Assistant Examiner* — Randall H Gholson(74) *Attorney, Agent, or Firm* — W. Scott Carson(57) **CLAIM**

The ornamental design for a portable entertainment module, as shown and described.

DESCRIPTION

FIG. 1 is a front perspective view of a portable entertainment module showing our design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof.

The portions of the design shown in broken lines form no part of the claimed design.
